(57) **CLAIM**

The ornamental design for a footwear article as shown and described.

DESCRIPTION

FIG. 1 is a right side view of a footwear article according to the claimed design.

FIG. 2 is a left side view of the footwear article.

FIG. 3 is a top view of the footwear article.

FIG. 4 is a bottom view of the footwear article.

FIG. 5 is a front view of the footwear article; and,

FIG. 6 is a rear view of the footwear article.

The broken lines in the drawings illustrate stitching and portions of the footwear article that form no part of the claimed design.

The surface line shading in the drawings is included for clarity.

1 Claim, 6 Drawing Sheets
